INSULATOR FASTENER

Harry M. Young, Webster Groves, Mo., assignor to
 Western Wire Products Company, St. Louis,
 Mo., a corporation of Missouri

Application July 28, 1938, Serial No. 221,766

4 Claims. (Cl. 174—157)

This invention relates generally to insulator-fasteners and, more particularly, to a certain new and useful improvement in an insulator fastener or clip particularly, though not exclusively, adapted for use in connection with metallic fence-posts and the like.

My invention has for its primary object the provision of an insulator fastener for the purpose stated, which is simple and inexpensive in structure, rugged and durable in use, and facile and convenient in installation, the fastener being very quickly and easily attached to any conventional fence-post and efficiently securing the insulator tightly in operative wire-supporting position against the face of the post.

And with the above and other objects in view, my invention resides in the novel features of form, construction, arrangement, and combination of parts presently described and pointed out in the claims.

In the accompanying drawing—

Figure 1 is a perspective view of an insulator-fastener embodying my invention;

Figure 2 is an enlarged transverse sectional view of the fastener, taken approximately along the line 2—2, Figure 1;

Figure 3 is a perspective view of the fastener in assembling association with an insulator;

Figure 4 is a fragmentary reduced perspective view of an end-embedded standing fence-post equipped with insulators held in place by fasteners of my invention;

Figure 5 is a longitudinal sectional view of an insulator-fastener of my invention operatively securing a two-piece insulator upon a fence-post of T-shaped cross-section;

Figure 6 is a similar view illustrating the fastener operatively securing a one-piece insulator upon a fence-post of angle or L-shape cross-section;

Figure 7 is a reduced perspective view of a slightly modified form of insulator-fastener embodying my present invention;

Figure 8 is a transverse sectional view of the modified insulator-fastener, taken approximately along the line 8—8, Figure 7; and

Figure 9 is a side elevational view of another slightly modified form of insulator-fastener embodying my present invention.

Referring now in more detail and by reference characters to the drawing, which illustrates practical embodiments of my present invention, the insulator-fastener or clip A is constructed preferably of a section of suitable so-called "half round"

wire-stock bent and formed to integrally include a main portion comprising an intermediate head 1 and a pair of companion or co-operable legs 2, 2', which latter are of suitable length and extend approximately at right angles from the head 5. The leg 2 constitutes one end-portion of the wire section from which the fastener or clip is constructed, and at the free end of the leg 2, the wire of the fastener is axially deflected in the provision of an offset-bend, as at 3, and then 10 lengthwise extended to provide a leg-continuation 4, which latter constitutes the other end-portion of the clip-wire and normally is approximately axially parallel to the leg 2, as best seen in Figure 1. As will be observed, the respective 15 flat faces a of the legs 2, 2', are in opposed relation for engagement, and normally the leg 2 is axially disposed outwardly at an angle to the axis of and is resiliently shiftable laterally for precise marginal registration with the companion 20 leg 2', for purposes presently more fully appearing and as best seen in Figures 1 and 2.

B designates a conventional two-piece insulator comprising a substantially cylindrical main or body-portion 5 and a co-operable circular or disk-shaped head 6, both constructed preferably of porcelain or other suitable dielectric material. The body-portion 5 is provided with an axially extending bore 7, and a pair of laterally spaced arcuate channels 8 extend across the upper face 30 of the body 5 equidistantly on opposite sides of the bore 7. The head 6 is adapted for peripheral registration with the body 5 and similarly has an axial bore 9 for co-axial alignment with the body bore 7 and a pair of end-face transverse 35 arcuate channels 10 for overlying registration with the body channels 8.

In use, the clip or fastener A has its legs 2, 2', and leg-continuation 4 inserted endwise through the registering axial bores 7 and 9 of the insulator body 5 and head 6, as best seen in Figure 3.

Now, in the erection of a so-called live-wire cattle fence or other structure, a plurality of fence-posts are embedded at an end in the ground 45 in any conventional manner. Such fence-posts are of suitable cross-section, usually T or angle. With a T-shaped post C, as in Figure 4, its flange 11 is provided with a plurality of suitably spaced openings 12. The leg-continuation 4 of a particular clip A having an insulator B mounted thereon is inserted endwise through a selected opening 12 and the insulator portion 5 shifted 50 rotarily upon the clip A until the channels 8 are horizontally disposed with respect to the ground 55

G for receiving the strand of a fence wire W. The clip A and the insulator head 6 are then shifted toward the particular post C until the insulator head 6 is brought into marginal registration with the insulator portion 5 and the channels 10 thereof are also in marginal registration with the channels 8 for retentively holding the fence wire strand W. The leg-continuation 4 of the clip A is then bent, as at 13, retentively around 10 the outer or free margin of the web 14 of the fence-post C, as best seen in Figure 5.

With a fence-post C' of angle or L-shape in section, one leg 15 of the post is similarly provided with a plurality of suitably spaced openings 16. For purposes of illustration, the post C' is shown in Figure 6 in conjunction with a so-called one-piece insulator B', which is also constructed of porcelain or other dielectric material and of substantially cylindrical form with an axial bore 17 and a circumferential channel or recess 18 adjacent its upper end for retentively receiving a wrapped around wire strand W'.

The clip A has its legs 2, 2', disposed through the bore 17 of the insulator B', the leg-continuation 4 being inserted endwise through a selected opening 16 and similarly, as at 19, bent around the outer margin of the other leg 20 of the fence-post C', as best seen in Figure 6, for securely fastening the insulator B' in operative wire-supporting position on the fence-post.

In the engagement of the clip A with either of the insulators B or B', the legs 2, 2', are yieldingly pressed into approximate flatwise abutment at their faces a and subsequently function in frictionally holding the particular insulators from bodily turning when in wire-supporting position upon a fence-post. I might add, however, that the clip may, for certain purposes and under certain circumstances, be constructed of wire-stock of circular cross-section of suitable diameter, as best seen in Figures 7 and 8. Also, in the case of relatively large-size insulator clips, such as the clip A'', Figure 9, which should preferably be formed of unusually stiff wire-stock, the leg-continuation 4' is preferably provided on its rounded face a' with a plurality of suitably spaced notches, as at 21, for facilitating the formation of the retentive fence-post engaging bend 13 at the proper location according to the size of the particular post.

It will be evident that, by my present invention, I have provided an insulator fastener or clip, which is economical in cost of production, durable in structure, and most convenient in installation, and it should be understood that changes and modifications in the form, construction, arrangement, and combination of the several parts of the clip may be made and substituted for those herein shown and described without departing from the nature and principle of my invention.

Having thus described my invention, what I claim and desire to secure by Letters Patent is—

1. In combination, an axially bored dielectric insulator, and a fastener comprising a first leg in engagement with the insulator along substantially the entire length of the insulator-bore, said leg having at one end a transversely extending head-portion and at its other end an axially extending leg continuation bendable for support 10 engagement, and a second leg connected at an end to the head-portion and normally extending yieldingly obliquely relative to, and in marginal registration with, the first leg, said second leg having resilient frictional engagement at its free 15 end only with the insulator.

2. In a combination, an insulator having a bore therethrough, and a split pin fitted in the bore and having a head at one end holding against the insulator, said pin having one leg 20 thereof of less length than the bore and having the other leg relatively longer than, and extending from, the end of the bore as a fastening portion and said legs being resiliently spread whereby said legs frictionally engage and hold within 25 the bore.

3. In combination, an axially bored insulator and a fastener having a head for engagement with an end of the insulator and a pair of legs each connected at an end to the head and 30 extending into the axial bore of the insulator, said legs being resiliently spread for frictionally engaging the insulator, one of said legs being substantially shorter than the insulator-bore 35 and the other of said legs being substantially longer than and extending from the end of the insulator-bore, said leg being angularly bent in the provision of an offset portion extending approximately to the longitudinal axis of the fastener in the provision of a leg-continuation extending substantially along the longitudinal axis of the fastener for engagement with a support.

4. In combination, a two-part insulator comprising coaxially bored body and head sections, and a fastener having a head member for 45 engagement with the outer end of the insulator head-section, a pair of laterally spaced legs resiliently connected at an end to the fastener-head and extending through the bores of the insulator head and body sections and being 50 spread apart for frictional engagement therein, one of said legs being shorter than the combined length of the bores of the insulator head and body sections and the other leg being longer than said combined bore-length and extending 55 from the bore in the provision of a fastening portion.

HARRY M. YOUNG.
